UNITED STATES PATENT OFFICE.

JOHN T. S. BROWN, JR., OF PROSPECT, KENTUCKY.

WORKING HEAD FOR DEEP-WELL PUMPS.

1,218,626.

Specification of Letters Patent. Patented Mar. 13, 1917.

Application filed November 4, 1916. Serial No. 129,431.

To all whom it may concern:

Be it known that I, JOHN THOMPSON STREET BROWN, Jr., a citizen of the United States, residing at Prospect, in the county of 5 Jefferson and State of Kentucky, have invented a new and useful Improvement in Working Heads for Deep-Well Pumps of which the following is a specification.

This invention relates to working heads of 10 the character used in connection with deep-well pumps.

Deep well pumps are operated with a long slow stroke, the pump rod being either directly connected to the piston of a slow speed 15 vertical engine, or connected by a pitman to a crank on a shaft driven from a suitable source of power. In such case the length of the crank is of course half that of the stroke of the pump, and the angle of transmission 20 varies continuously with consequent loss of efficiency.

An object of this invention is to provide a device of the character described which will be economical in construction, which will be 25 strong and durable and which will most efficiently perform the functions for which it is intended.

With the foregoing and other objects in view, the invention consists of the novel construction and arrangement of parts illustrated in the accompanying drawings, which form a part of this specification, wherein is set forth an embodiment of the invention, but it is to be understood that such changes 35 and modifications may be resorted to as come within the scope of the claims appended hereunto.

In the accompanying drawings, comprising three sheets, wherein similar reference characters designate like parts in the several views, Figure 1, is a front elevation of an embodiment of the invention with parts broken away to show the construction: Fig. 2, a side elevation, parts being broken away: 40 Fig. 3, a section on line 3—3 of Fig. 1: Fig. 4, a perspective view of the transversely sliding member: Fig. 5, a perspective view of the ball retainer on the transverse member: Fig. 6, a section on line 6—6 of Fig. 1: Fig. 50 7, a sectional detail.

Referring now to the drawings, the reference character —10— designates a well casing, —11— a pump head, which is attached to and closes the casing, —12— a discharge pipe, and —13— a pump rod which extends through a stuffing box —14—, down-

ward into the casing to a connection with the plunger. A bed-plate —15—, of suitable construction, is provided on its forward side with a semi-circular recess, or depression 60 which fits about the pump head, to which it is secured by suitable means such as bolts —16— which extend through flanges —17— extended from the opposite sides of the pump head. This method of connection 65 permits the bed-plate, with its super-incumbent structure, to be detached from the pump head and be moved back out of the way for the purpose of withdrawing the plunger from the well casing. A frame —20— is 70 erected on the bed plate. This frame may be constructed in any suitable manner, but preferably of angle iron, suitably braced. It comprises two side members —21 and 22— rigidly connected and spaced apart by transverse girders —23, 24, 25—. A shaft —26— mounted in bearings —27— on the girders 23 and 24 is provided with tight and loose pulleys —28, 29— whereby motion may be transmitted to it from a suitable source of 80 power. A gear wheel —30— is secured on the forward end of the shaft, and a reduced portion, or pin —31— extends axially slightly beyond the plane of the gear wheel and an annular ball bearing —32— is positioned thereon. Vertical guide rods —35— are suitably supported in front of the frame and cross-heads —36, 37— are slidably positioned thereon. The cross heads are held in spaced relationship by tie-rods —38—. The 90 pump rod is connected to the cross heads by suitable means such as clips —39—. The upper end of the rod and its respective clip is screw threaded to provide a firmer hold. A plate —40— is slidably mounted between 95 the cross-heads, on each end of this plate are secured steel plates provided with V shaped ways —41— which correspond with similar ways —42— in plates —43— which are affixed to the opposed faces of the cross-heads, steel balls —44— being disposed in the ways and retained therein by means of plates —45—, any lost motion caused by wear of the ways, or balls may be taken up by adjusting nuts —33— on the tie rods. 100 To the rear side of the plate 40 an elongated gear —46— is secured with which the gear wheel 30 meshes. The gear 46 comprises parallel sides joined by semi-circular ends, the length of the gear being the same as the 110 stroke of the pump. A runway, or channel —47— formed in the plate 40 conforms in

- outline with the elongated gear and is of such depth and width as to receive the ball bearing 32 on the end of the shaft and is spaced from the gear so that when the pin 5 31, and associated ball bearing is disposed in the runway the gear wheel will be engaged with the elongated gear and will be so maintained. As the gear wheel is rotated it causes the elongated gear and associated 10 parts, the cross-heads and pump rod, to move longitudinally in alternate directions, as the gear wheel engages with the respective sides of the elongated gear. When the gear wheel engages with the end sections of 15 the elongated gear, the gear wheel being held stationary in its bearings, the plate 40 is perforce shifted laterally between the cross-heads. It will be observed that the distance between the center of the shaft and the point 20 where the power is applied, *i. e.* the centers of the gear teeth, is constant and considerably less than is the case where the pump rod is connected by a pitman rod to a crank. 25 In my device the angle at which the power is transmitted is substantially constant, while with the crank connection the angle of transmission varies continuously, consequently a considerable saving in power is obtained by the use of my improved device. 30 It is thought that the construction, operation and many advantages of my invention may readily be understood by those skilled in the art, and having so described it,

I claim:

1. A frame, guide rods carried thereby, 35 adjustably spaced cross heads positioned on said rods, a plate slidably mounted between said heads, a rack secured on said plate, a shaft rotatably mounted in said frame, a gear wheel on said shaft meshing with said 40 rack and a pump rod connected with the cross heads.

2. A frame, guide rods carried thereby, 45 adjustably spaced cross-heads positioned on said rods, a plate slidably mounted between said heads, a rack secured on said plate, a shaft rotatably mounted in said frame, a gear wheel on said shaft meshing with said 50 rack, said plate having a runway conforming in outline with said rack, and an axial extension of the shaft entered in said runway and traveling therein.

3. A frame, guide rods carried thereby, cross heads slidably mounted thereon, rods connecting and maintaining said cross heads 55 in adjustable spaced relationship, a plate slidably mounted between the heads, a rack secured on said plate, a shaft rotatably mounted in said frame, a gear wheel on said shaft and meshing with said rack, the plate 60 having a runway which follows the contour of the rack, the shaft having a terminal reduced portion and an annular ball-bearing thereon, said ball-bearing entered in said runway and traveling therein.

JOHN T. S. BROWN, JR.
